UNITED STATES PATENT OFFICE.

NELS LARSON, OF DULUTH, MINNESOTA.

DESIGN FOR A COMBINATION-TOOL.

56,979.

Specification for Design. Patented Jan. 25, 1921.

Application filed April 8, 1920. Serial No. 372,368. Term of patent 14 years.

To all whom it may concern:

Be it known that I, NELS LARSON, a citizen of the United States, residing at Duluth, in the county of St. Louis and State of Minnesota, have invented a new, original, and ornamental Design for a Combination-Tool, of which the following is a specification, reference being had to the accompanying drawing, forming part thereof.

The illustration represents a side elevation of a combination tool, embodying my new design.

I claim:

The ornamental design for a combination tool, as shown.

NELS LARSON.
